INDICATING BOARD FOR ELECTRIC
POWER NETWORKS

George Arthur Burns, Liverpool, England, assignor to Automatic Electric Laboratories, Inc., Chicago, Ill., a corporation of Delaware

Application March 30, 1945, Serial No. 585,669
In Great Britain April 27, 1944

2 Claims. (Cl. 175—298)

1

The present invention relates to indicating boards suitable for use in signalling systems for remote supervision and/or control of electric power transmission systems or the like. It is more particularly concerned with boards of the mimic line diagram type built up from a plurality of detachable and interchangeable units or escutcheons each of the order of 1 inch square, each unit being either blank or having a symbol thereon depicting a small section of the line diagram of which it forms part.

The object of the invention is to provide an improved form of mimic line diagram of this type in which certain of the escutcheons each depicting a small section of the line diagram carry electric switches for controlling the apparatus represented thereby, and in which certain other escutcheons are arranged to be translucent so as to enable the light from supervisory lamps to be observed therethrough, thereby avoiding lamp cap fittings on the front of the diagram which thus presents a smooth and pleasing appearance and can readily be kept clean.

According to one feature of the invention, in an indicating board of the mimic line diagram type made up of a plurality of detachable and interchangeable units of identical shape, control equipment corresponding to the appropriate units is mounted exclusively behind the board and is arranged to be effective from the front side without the provision of any projections or apertures in the front surface so as to maintain this surface smooth and unbroken.

According to another feature of the invention, in an indicating board of the mimic line diagram type made up of a plurality of detachable and interchangeable units of identical shape, certain of the units forming a section of the line diagram include a rotatable circular portion normally flush with the front surface the movement of which portion by an attendant is arranged to actuate an electric switch controlling the piece of apparatus represented by the unit.

A further feature of the invention is that in an indicating board of the mimic line diagram type made up of a plurality of detachable and interchangeable units of identical shape, the individual units are made of translucent material with a portion of reduced thickness and arrangements are provided for mounting a lamp behind the board closely adjacent to the reduced portion so that the lighting of the lamp is clearly visible from the front.

The invention will be better understood from the following description of one method of carrying it into effect, reference being had to the accompanying drawing comprising Figs. 1 and 2

2

which show front and side views respectively of a portion of an indicating board constructed according to the invention, Figs. 3, 4 and 5 which show top views of the escutcheon plates seen in Figure 2, and Fig. 6 which is a cross sectional view showing in detail how the switch escutcheons are mounted.

Referring to Fig. 1, the escutcheon plates such as 10 are preferably moulded from plastic material and have square front faces as shown so that they may be pieced together on the perforated metal panel 11 to build up the complete diagram. The small section of the line diagram depicted by escutcheon 10 takes the form of a shallow channel which is filled in with a suitable colouring material. As will be seen from Fig. 2 those escutcheons such as 10 which do not carry an electric switch are provided with a stem 12 which passes through a hole in the panel 11 and is provided with a circular groove 13 which accommodates the forked flat spring member 14 which secures the escutcheon firmly in position on the panel.

The escutcheon 15 carrying the electric switch is shown more clearly in the side and cross sectional views. It is provided with a rotatable plastic disc 16, conveniently of the same material as the other escutcheons, which carries a portion of the line diagram and is normally flush with the panel. It can, however, be depressed with the finger and turned to actuate the electric contact springs 17 to perform certain circuit controlling functions which result in the remote selection of the piece of apparatus depicted by this switch in the diagram, for example a circuit breaker.

As will be seen from Fig. 2 or 6 the rotatable disc 16 is provided with a stem which passes through to the rear of the panel and carries at its end an insulating block 18 located between the moving springs of the contact assembly. Normally, the rotatable disc 16 as seen from Fig. 2 or 6 is urged into the position shown, that is, flush with the face of the panel, by a spring 19 which encircles the plunger stem and is housed in a suitable cavity provided partly in the plastic escutcheon and partly in a metal block 20 which forms a backing member to the panel. Fastened also to the metal block 20, by the screws shown, is the L-shaped bracket 21 supporting the contact spring assembly.

When it is desired to open the circuit breaker represented in the mimic diagram by the escutcheon 15 in question, the operator depresses with his finger the rotatable disc 16 against the tension of the spring 19 so that a plunging action is performed, and the metal backing piece 22

located behind the spring operating block 18 is moved axially out of engagement with a V-shaped locating slot not visible in the drawing. When this is done, the disc 16 can be rotated so that the portion of the line diagram it carries assumes a horizontal position on the panel thus giving a pictorial representation of the open condition of the circuit breaker it represents. In this position the inner contacts of the assembly 17 are broken and the outer contacts are made as a result of displacement of the moving springs by the insulating member 18 which is rectangular in shape and hence its longer dimension assumes a vertical position when the line on the disc assumes a horizontal position on the panel. In this position the member 22 again moves into a V-shaped slot, not visible in the drawing, to locate the line on the disc in its correct horizontal position.

In explanation of the circuit change which takes place as a result of operation of the switch, it should be mentioned that at all times when the switch in the diagram is out of line with the circuit breaker it represents, an indicating lamp such as 25 is lighted adjacent to the switch, and remains lighted until such time as the indication on the panel is in agreement with the condition of the circuit breaker. If the position of the switch is changed manually, the lighting of the lamp may indicate that the associated circuit breaker has been selected and can then be made to change its position by the pressing of a common "operate" button. Thus in the case in question, when the switch has been operated to bring about a change of condition of the circuit breaker, the lamp remains alight until the circuit breaker has actually changed its position. Under other conditions when say the circuit breaker automatically trips on fault, the lamp adjacent to the escutcheon 15 again lights to call attention to the difference in condition of the circuit breaker and the diagram and remains lit until the operator turns the disc to coincide with the new position of the circuit breaker.

The lamp is arranged to be mounted on the spring member 23 which is identical with the spring member 14. The lamp holder 24 and lamp 25 are supported by an L-shaped metal member 26, the longer limb of which is provided with turned-over edges. These edges enable it to slide on to the upstanding portion of the spring member 23 which thus gives the necessary support. A sheet metal shade or screen 27 bent into roughly the form of a cylinder serves to restrict the light to the desired area, namely the reduced central portion of the associated escutcheon. This member is provided with turned over edges which engage in the similar edges on the support 26 and retain the member 27 in position.

It will be appreciated that the escutcheons which provide lamp mountings may be identical with all the other escutcheons except those carrying switches and as a result the lamps may readily be moved and located in the position where they are most useful. It is found that the indication given by a lamp is readily visible from the front of the board, even from a direction of considerable obliquity, and the additional advantage is obtained that there is no necessity for lamp caps or the like to break the front face of the diagram. The lamps may be of any suitable type meeting the dimensional limitations, for instance of the type employed in telephone exchanges.

The arrangements for securing the special escutcheon 15 to the panel 11 are not quite so sim-

ple as in the case of the plain escutcheons such as 10 and 28. The construction, as shown in Fig. 6, is that the screw on the end of the block 18 threads into the stem of the rotatable disc 16 so that when the screw is removed the disc and stem can be withdrawn. This exposes a headed tubular bolt 30 which screws into the metal block 20 and thus clamps the escutcheon 15 to the frame 11. It may be mentioned that if thought desirable the rotatable centre portion of the escutcheons such as 15 may be provided with a slightly raised bar along the line of the diagram so as to facilitate the operation of turning.

According to the invention therefore a mimic diagram is provided which may readily be built up to represent any desired system and which while permitting control of the circuit breakers and the like from the symbols which represent them still presents a clear and attractive appearance which can readily be kept clean.

What I claim as new and desire to secure by Letters Patent is:

1. In an electrified line diagram board, a base panel having a plurality of apertures in spaced quadrature relation therein and a plurality of small interchangeable escutcheons mounted side by side on said panel, stems attached to one face of each of said escutcheons and extending through said panel apertures, retaining means associated with said stems for maintaining said escutcheons in abutting relationship with said base panel, said retaining means being concealed from the faces of said escutcheons, a mimic pattern defined by said escutcheons, and electric control switches mounted behind certain of said escutcheons.

2. In an electrified line diagram board, a base panel having a plurality of apertures in spaced quadrature relationship therein, a plurality of small interchangeable escutcheons mounted side-by-side on said panel, stems attached to one side of each of said escutcheons and extending through said panel apertures, spring means associated with said stems for maintaining said escutcheons in abutting relationship with said base panel, said spring means being visible only from the stem side of said escutcheons, and a mimic pattern defined by said escutcheons.

GEORGE ARTHUR BURNS.
